SECTIONALIZED UNIT FOR A PICKET SLAT FENCE

Gerard R. De Paolo, 5 Dorset Drive,
Kenilworth, N.J. 07033

Filed June 20, 1966, Ser. No. 2,743

Term of patent 14 years

(Cl. D28—1)

FIG. 1 is a front elevation of a sectionalized unit for a picket slat fence, embodying my new design;

FIG. 2 is a rear perspective view with illustration of a holding stake applied to the rear thereof;

FIG. 3 is a top plan view looking in the direction of the arrows 3—3 of FIG. 1, and

FIG. 4 is a front elevation of a modified embodiment of the sectionalized unit shown in FIG. 1;

FIG. 5 is a rear elevational view thereof, with an illustration made of holding stake applied to the rear thereof, and

FIG. 6 is an enlarged cross sectional view taken on line 6—6 of FIG. 4 thereof.

The broken lines are shown for illustrative purposes only.

I claim:

The ornamental design for a sectionalized unit for a picket slat fence, substantially as shown and described.
